CONTAINER

Helen G. Grant, Asheville, N. C.

Application January 16, 1937, Serial No. 120,969

7 Claims. (Cl. 206—44)

This invention relates to packages, and more particularly to containers intended primarily for the packaging of perishable goods such as cakes and other bakery products of a soft and sticky nature. The invention is likewise directed to a method of forming the container.

During more recent years it has become the custom to package various products, including cakes, in a manner which will shield the same from dust, dirt, flies and the like. Since such bakery products are now usually distributed over larger territories than was customary only a relatively few years ago and are therefore subjected to added handling, many attempts have been made to not only apply protective wrappings to the products but to apply said protection while to a limited extent protecting the soft and tacky products from damage from normal shocks and jars. While containers already known in the art have proven successful to a limited degree in protecting cakes and the like they have not proven entirely satisfactory for the reasons that they are objectionable from the standpoint of expense or do not provide the desired degree of exhibition of the product without damage to the surface of the contained goods.

It is an object of the present invention to provide a container for cakes and other perishable products which overcomes the difficulties heretofore encountered in the art. The invention contemplates the provision of such a container which is durable in service, capable of being produced and utilized at small expense, and yet one which is ornamental and permits the substantially unobstructed display of the packaged product.

A further object of this invention is the provision of a simple, yet efficient method by which the supporting elements for the present container may be stamped from sheets of relatively inexpensive material in a condition ready for assembly.

This invention further contemplates utilization of arched crossed frame members secured to a supporting base in which the arched members overlie the contained product and impart greater resistance to strain in a direction perpendicular to the base of the package, and in which the arched members are caused to resist circumferential movement by an outer transparent wrapping sheet.

Other objects and advantages will be apparent from the following detailed description when considered in connection with the accompanying drawing wherein;

Fig. 1 is an illustration of a blank sheet from

which the arched members and supporting plate of the present container are shown severed by stamping;

Fig. 2 is a top plan view of the assembled arched members and supporting plate made in accordance with this invention;

Fig. 3 is a transverse sectional view along the line 3—3 of Fig. 2 through a completely wrapped and filled container formed according to this invention; and

Fig. 4 is a perspective view of the completed and filled package.

Now in referring to the drawing in detail, the sheet material from which the more rigid members of the present package are stamped by a die is illustrated at 10. This sheet is preferably cardboard, light wood ply or wood pulp board or sheet metal, for although many materials are capable of being utilized from the mechanical standpoint, in a device of the present nature low cost of production is of decided importance. Mat board tough check railroad ply has been found to be very satisfactory for this purpose.

Sheet 10 is stamped in a manner to permit as complete utilization as possible. It has been found that in packaging products of the type referred to above that the stamped sections 11 of the shape indicated are particularly suitable since the rounded corners 12 formed with the slots 13 constitute projections which act as fastening means for the sections 14 after they are assembled in the manner to be hereinafter more fully described.

Sections 14 as stamped are constituted of the material in sheet 10 immediately bordering the respective sections 11, and the sections 14 are separated from each other at 15. Additionally the cutting die is so constructed that a slot 16 is formed in one section 14 of each pair at the center portion thereof with the slot extending inwardly from its edge adjacent section 11, while the other section 14 has a similar slot 17 extending inwardly from its edge remote from section 11.

It will be seen that the parts of the container described above are in the form of flat thin sections, they having been stamped from flat sheets without being distorted. Hence the sections may be readily shipped and stored in large quantities without requirement of a prohibitive amount of space.

In utilizing the present container in the packaging of products, a base section 11 is placed on a flat surface and a pair of arched sections 14 are secured together by placing the arched sec-

tion provided with slot 16 over and perpendicular to the section having slot 17 and the sections are then pressed together.

The method of wrapping the more rigid parts 5 of the container may be by wrapping in a sheet of cellophane in any known manner but it is preferable that the sheet be folded under the base with its folded portions being secured by an adhesive, by sealing or by clips. The wrapping sheet 10 not only affords a protection for the product against dust, flies and the like but it additionally provides a frictionally contacting restraining means for the arched members 14. Since the arched members are with the elongated dimensions 15 of their cross sections extending perpendicular to the base of the package so as to resist compressive action said members normally present little resistance to transverse movement. However since the wrapping sheet closely engages the arched members the frictional contact 20 had therewith materially aids the arched members and enables the entire package to resist shocks and the like as a unit.

When an article such as a cake is packaged in 25 the manner described it will not only withstand the shocks of transportation in a large measure because any force tending to displace the cake will cause the cake to first contact the supporting members which will make a slight indentation 30 in the surface of the cake instead of damaging a substantial portion of the surface thereof as would occur if the cake were packed in a box but the cake will be displayed in a substantially unobstructed manner with enhanced "eye appeal". 35 It will be clear that the covering of the container does not contact the cake as is the case when a cake is directly wrapped in a material such as paper or cellophane. When, as in the past, the wrapping itself is permitted to contact with the 40 surface of a cake or other soft, sticky article, a portion of the surface of the article adheres to the wrapping and the surface of the product is thereby destroyed.

The present container permits practically unobstructed view of the contained article due to 45 the thin nature of the supporting members. Heretofore in the use of inexpensive packages, unobstructed vision has been obtained only by directly wrapping the article, such as a cake, in cellophane which adhered to the sticky surface 50 of the cake and damaged the appearance thereof in the manner set forth above.

The light weight and strength of the present container make it possible to handle the package 55 in the ordinary commercial manner at little, if any, increase over the cost of handling the article alone. Furthermore the article may be displayed in the same container in which it is shipped and the use of the arched members to form a 60 hood over the product permits of color combinations of the parts of the container and the product which produce the desired appeal to the purchasing public.

While the particular shapes and construction 65 of the parts of the container have been specifically set forth above, it is to be understood that modifications in the various shapes and details of construction are contemplated within the scope of this invention.

70 What I claim is:

1. A container comprising a base for supporting a product, and a hood formed of a plurality of arch strips in overlying relation to and each attached at its opposite ends to said base and a

sheet of covering material overlying said arches and being secured against the under side of said base, each of said arch strips being relatively thin and of relatively great width and positioned with the greater dimension thereof lying in a 5 plane perpendicular to the surface of the said base.

2. A container comprising a base for supporting a product and a hood formed of a plurality of intersecting arch strips in overlying relation 10 to and each attached at its opposite ends to said base, each of said arch strips being relatively thin and of relatively great width and positioned with the greater dimension thereof lying in a 15 plane perpendicular to the surface of the said base.

3. A container comprising a base for supporting a product, and a hood formed of a plurality of intersecting arch strips being relatively thin 20 and of relatively great width and a sheet of covering material, each of the said strips being fitted at its opposite ends into notches in the base with the greater dimension thereof perpendicular to the surface of the said base.

4. A container comprising a base for supporting 25 a product, and a hood formed of a plurality of intersecting arch strips being relatively thin and of relatively great width and a sheet of covering material overlying said arches and being secured against the under side of said base, the said 30 strips being connected by means of notches in the said strips and attached to the said base with the greater dimension of each of said strips perpendicular to the said base.

5. A container for display and protection, particularly adapted to contain circular products, comprising a base of substantially rectangular outline with rounded corners and convex sides and having a notch at each of the said corners, a pair of arched members conforming in outline 40 to the outline of the base, said arched members being provided with notches at the middle thereof whereby they are connected together in perpendicular relation, the pair of connected arched members having their ends inserted in the said 45 notches at the corners of the base member, the whole being covered by a transparent sheet material, the said container being characterized by its resistance to strains tending to distort the same.

6. A package containing an article for protection and display comprising a base of substantially rectangular outline with rounded corners and convex sides and having a notch at each of the said corners and a pair of arched members conforming in outline to the outline of the base, said arched members being provided with notches at the middle thereof whereby they are connected together in perpendicular relation, the pair of connected arched members having their ends inserted in the said notches at the corners of the base member, the whole being covered by a transparent sheet material, the said container being characterized by its resistance to strains tending to distort the same.

7. An enclosure comprising a base member and at least two arched members formed from sheet material connected at their ends to said base member and spaced intermediate their ends above said base member, each of said arched members being positioned with the greater dimension thereof lying in a plane perpendicular to the surface of said base member.
